UNITED STATES PATENT OFFICE.

WILLIAM DURHAM SARGENT, OF CHICAGO, ILLINOIS.

DESIGN FOR A BRAKE-HEAD.

SPECIFICATION forming part of Design No. 31,000, dated June 13, 1899.

Application filed May 19, 1899. Serial No. 717,503. Term of patent 14 years.

To all whom it may concern:

Be it known that I, WILLIAM DURHAM SARGENT, a citizen of the United States, residing at Chicago, in the county of Cook and State 5 of Illinois, have invented certain new and useful Improvements in a Design for a Brake-Head, of which the following is a specification.

My design is illustrated in the accompanying drawings, in which—

- 10 Figure 1 represents a sectional elevation of a brake-head embodying my invention. Fig. 2 is a top plan view thereof. Fig. 3 is an inverted plan view thereof, and Fig. 4 is a transverse vertical central section.
- 15 The leading feature of my design consists of a generally rectangular casting which is arched when viewed from the side and which in plan view is shown as having squared straight end portions and a cylindrical hollow portion, with straight ends and intermediate portions connecting the central and end portions with an ogee curve. In each end is formed a semicircular notch, which gives to the ends a generally U or forked shape in 25 plan view.

Referring now to the drawings, the brake-head consists of an arched frame A, the center of which rises above the arch to form a

semicircular projection B, which is perforated axially to render the same cylindric. The 30 arch terminates in bifurcated or forked ends C, the sides of the arch between each end and the central cylindric extension being formed on ogee curves, as at D, the ends of the cylindric extension and the sides of the ends C 35 of the arch being straight and parallel. At or about the point of conjunction between the ends of the semicircular extension B and the arch the arch is provided with depending and generally rectangular frames E, which extend 40 beneath the arch transversely and from side to side thereof.

The arch shape of the body of the brake-head, with the central semicircular extension, bifurcated ends, and curved sides, gives to 45 the brake-head a characteristic and distinguishing appearance.

Having thus fully described my invention, what I claim, and desire to secure by design Letters Patent, is—

The design for a brake-head, substantially as herein shown and described.

WILLIAM DURHAM SARGENT.
